HENRY G. REED, OF TAUNTON, MASSACHUSETTS, ASSIGNOR TO

Design No. 3,302, dated December 29, 1868.

DESIGN FOR A SPOON OR FORK-HANDLE.

The Schedule referred to in these Letters Patent and making part of the same.

To all persons to whom these presents may come:

Be it known that I, HENRY G. REED, of Taunton, in the county of Bristol, and State of Massachusetts, have invented or produced a new and ornamental Design for a Handle for a Spoon, Fork, or other article of plated or silver-ware; and I do hereby declare the same to be fully described in the following specification, and represented in the accompanying drawings, of which—

Figure 1 is a front view, and

Figure 2, an edge view of such handle.

At its top, the handle is formed with a shield, *a*, containing the helmeted head, *b*, of a warrior, in *bas-relief*.

From this a bead, *b'*, extends along each of the edges of the handle, and terminates in a volute, *c*.

Between the volutes and the shield is a smaller shield, *d*, containing a radiated rosette, *e*, formed as represented.

I claim, as my invention or production—

The design, substantially as above explained, and as represented in the accompanying drawings.

H. G. REED.
